UNITED STATES PATENT OFFICE

91,584

DESIGN FOR A LAMP

James P. Kiernan, Derby, Clyde G. Cottle,
West Haven, and William J. Sheehan, New Haven, Conn., assignors, by mesne assignments, to Louis J. Kasden, Ansonia, Conn.

Application July 21, 1933. Serial No. 48,788

Term of patent 3½ years

To all whom it may concern:

Be it known that we, JAMES P. KIERNAN, CLYDE G. COTTLE, and WILLIAM J. SHEEHAN, citizens of the United States, residing at Derby, West Haven, and New Haven, all of county of New Haven, State of Connecticut, have invented a new, original, and ornamental Design for a Lamp, of which the following is a specification, reference being had to the accompanying drawing, forming part thereof.

The figure is a perspective view of a lamp, showing our new design.

We claim:

The ornamental design for a lamp, substantially as shown.

JAMES P. KIERNAN.
CLYDE G. COTTLE.
WILLIAM J. SHEEHAN.
